Primary Examiner — Robert M Spear*Assistant Examiner* — Rhea Shields(74) *Attorney, Agent, or Firm* — Panitch Schwarze Belisario & Nadel LLP(57) **CLAIM**

The ornamental design for a medicate container, as shown and described.

DESCRIPTION

FIG. 1 is a front perspective view of a medicate container in accordance with a preferred embodiment of our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken lines in the figures are for the purpose of showing environmental structure and form no part of the claimed design.
